UNITED STATES PATENT OFFICE.

OTTO C. BUELDT, OF ST. LOUIS, MISSOURI.

BREAD-LABELING DEVICE.

1,306,745.

Specification of Letters Patent. Patented June 17, 1919.

Application filed February 9, 1917. Serial No. 147,549.

To all whom it may concern:

Be it known that I, Otto C. BUELDT, a citizen of the United States, residing in the city of St. Louis and State of Missouri, have 5 invented a new and useful Bread-Labeling Device, of which the following is a specification.

It is a well-known fact that all loaves of bread are usually labeled with two labels, 10 one, the union label, and the other, the baker's label, these labels being applied to the loaves after they have passed through the loaf-molder and prior to baking, and it is my object to cause each loaf to label itself while passing through the loaf-molder, 15 thus obviating the necessity of the expensive method of labeling loaves of bread by hand.

Briefly, and broadly, my labeling device 20 consists of a roll of labels, loaf actuated label advancing mechanism, a label cutter, and a labeling plate.

My invention relates more particularly to 25 an attachment for loaf-molders for placing gummed printed labels upon the loaves prior to their leaving the loaf-molder. And the objects of my invention are, first, to provide a loaf actuated plate to be arranged in the bottom of the loaf-molder in the path of 30 travel of a loaf; second, to provide means adapted to be actuated by the movement of the loaf actuated plate for imparting movement to a label advancing mechanism; third, to provide labeling plates in the loaf-molder 35 in the path of travel of a loaf; fourth, to provide means for guiding the printed gummed labels from a feed roll to the labeling plates; fifth, to provide loaf actuated label advancing means; and sixth, to pro- 40 vide means for returning the loaf actuated plate to its normal uppermost position after having been depressed by means of a passing loaf.

With the above and other objects in view, 45 my invention consists in the novel arrangement and combination of parts as will be more fully described hereinafter, and finally pointed out in the claims hereto appended.

Referring to the accompanying drawings 50 forming a part of this specification wherein like characters of reference denote similar parts throughout the several views,

Figure 1, is a sectional view of the lower portion of a loaf-molder with my labeling 55 device applied thereto.

Fig. 2, is a plan view of the loaf-molder

and labeling device with the loaf-molder roller removed, and the labeling device mostly shown in dotted lines.

Fig. 3, is a detail of the label guiding 60 means and the label cutter.

Referring to the drawings, the reference character 1 designates the bottom wall of a standard loaf-molder; 2, a loaf-molder roller; and 3, the space or channel between 65 the bottom plate 1 of the loaf-molder and the periphery of the roller through which a loaf is adapted to roll in passing through the molder.

In carrying out the aim of my invention, 70 I provide the bottom 1 of a loaf-molder with a suitable opening or cut-away portion 4.

A depressible loaf actuated plate 5 is adapted to be arranged in the opening 4. The plate 5 is preferably somewhat less in 75 size than the opening 4 so as to permit flour to fall between the edges of plate 5 and opening 4 instead of clogging, as would be the case if it could not easily pass between the two elements. The plate 5 is preferably 80 provided with an inclined upper surface 6 which, if found desirable, may be slightly roughened or serrated. The inclined surface 6 it will be observed grows higher toward the rear of the loaf-molder, and the 85 object thereof will be more fully set out hereinafter.

The depressible plate 5 is guided and held in proper position by means of a pair or more of supporting legs 7, and the upper 90 end of each leg 7 is fixed to the plate 5. The legs 7 each preferably pass through a pair of ball-bearing holders 8, which holders are carried by means of the cross-piece 9 and the arms 10 of each supporting bracket 11. 95 Each supporting bracket 11 is suitably fixed to the bottom wall 1 of the loaf-molder. The lower end of each leg 7 is connected by means of a cross-bar, or its equivalent, 12. A suitable spring-means 13 is connected at its upper end to the cross-bar 9, and at its lower end to the cross-bar 12 for the purpose of normally holding the loaf actuated plate 5 in its uppermost position and for returning the plate 5 to its uppermost position after 100 having been depressed by means of a loaf rolling over the same in passing through the molder.

Pivotedly connected to the cross-bar 12, as at 14, is a connecting link 15. The arm 110 15 is pivotally connected at its lower end, as at 16, to a suitable sprocket 17, which

sprocket is rotatably mounted in a suitable bearing 18.

Arranged at a suitable location adjacent the bottom 1 of the loaf-molder is a shaft 19 supported at each end by means of suitable bearings 20. A sprocket 21 is fixed to the shaft 19, and an endless chain 22 is adapted to connect and pass over the sprockets 17 and 21, as clearly shown in 10 Fig. 1.

The reference character 23 designates a feed roll of gummed and printed labels mounted upon a bearing 24.

The gummed labels 23 are adapted to pass 15 between a preferably serrated driven roller 25 and an idler 26, then through a guide means 27 to a preferably metallic labeling plate 28, which plate is arranged upon the bottom 1 of the loaf-molder and within the 20 loaf passage 3 slightly in advance of the loaf actuated plate 5. The label-guide 27 is supported by means of the suitable supports 29, and the roller 26 is preferably supported by means of the label-guide 27. The roller 25 25 is fixed to the shaft 19, and the labels are adapted to pass between the rollers 25 and 26 with the gummed side up.

An elastic label-cutter 30 is secured to a suitable holder 31 and is adapted to pass into 30 the loaf passage 3. The inner extremity of the cutter 30 is provided with a suitable knife-edge 32 adapted, when depressed by a loaf rolling over the same, to sever the label lying upon the labeling plate 28 from the 35 next label of the roll attached thereto. As the loaf A rolls over the label in passing through the loaf-molder, the loaf, due to its expansive force and moist periphery, causes the label to stick to the loaf, and as the loaf 40 depresses the plate 5 by rolling over it, it actuates the mechanism for advancing the next label for the following loaf, as is manifest.

For convenience I have described only one 45 set of rollers 25 and 26, one label-guide 27, one labeling plate 28, and one label-cutter 30, but by referring to Fig. 2 of the drawings, it will be observed that two sets are 50 illustrated showing that two labels may be applied to a loaf at the same time. More than two labels can be applied, as is manifest.

The reference character 33 designates electric conductors leading to the labeling 55 plates 28 for the purpose of heating the plates 28 in cold weather, thus causing the labels to more readily adhere to the passing loaves A.

The operation of the device, is as follows, 60 assuming that a label 23 is already in position upon the labeling plate 28:

The loaf A as it rolls in the direction of the arrow shown in Fig. 1, due to the revolving movement of the roll 2, first passes 65 over the cutter 30 causing the knife-edge 32

to sever a label. This label adheres to the periphery of the loaf as it passes over the label. As the loaf rolls on it comes upon a depressible plate 5 having an inclined upper surface causing the plate 5 to be depressed as the loaf rolls over it. The depressing movement of the plate 5 imparts rotary movement to a sprocket 17 by means of a connecting link 15, which sprocket through the means of the chain 22 imparts movement to the sprocket 75 21 and rollers 25 and 26 causing the next label 23 to advance to a position upon the labeling plate 28 ready to be severed by the cutter and applied to the next passing loaf.

From the foregoing description it will be 80 observed that I have provided an automatic loaf-actuated mechanism for labeling loaves passing through a loaf-molder. It will be remembered that each loaf labels itself as it passes through the molder.

The many advantages of the herein described device will readily suggest themselves to those skilled in the art to which it appertains.

It will be understood that various changes 90 may be made in the details of construction within the scope of the appended claims, and therefore I do not wish to limit or be limited to the precise details shown and described, but wish it to be distinctly understood that 95 any modified or equivalent constructions are simply modifications of my labeling device, and such modifications as come under the scope of this specification and the appended claims, I consider within the spirit of my 100 invention.

What I claim is:

1. A labeling device for loaf molders comprising a loaf actuated plate arranged in an opening in the bottom of a molder in such a manner that the plate may be depressed by the loaf rolling over the same, means for returning the plate to its uppermost position after the loaf has passed over the same, label advancing mechanism, means actuated by the loaf actuated plate for actuating said label advancing mechanism, label guiding means, and label cutting means adapted to be actuated by a loaf rolling over the same.

2. A labeling device for loaf molders comprising a loaf actuated plate arranged in an opening in the bottom of a molder in such a manner that the plate may be depressed by a loaf rolling over the plate, means for returning the plate to its uppermost position after a loaf has passed over the plate, label advancing mechanism for bringing a label into the path of travel of a loaf for application thereto by the loaf rolling over the label, means for actuating said label advancing mechanism, and a loaf actuated means for cutting the labels from a roll adapted to be supported adjacent the label advancing mechanism prior to the label being applied to a loaf rolling over the same.

3. A labeling device for loaf molders comprising a loaf actuated plate arranged in an opening in the bottom of a molder in such a manner that it may be depressed by a loaf 5 rolling over the plate, means for returning the plate to its uppermost position after a loaf has passed over the plate, label feed rolls, a label guide through which the labels are adapted to pass into the path of travel of

a loaf, label cutting means adapted to be 10 actuated by a loaf rolling over the same, and means actuated by the loaf actuated plate for revolving the label feed rolls for advancing the labels one at a time for application to a loaf.

15

In testimony whereof, I have hereunto signed my name to the specification.

OTTO C. BUELDT.
